UNITED STATES PATENT OFFICE.

HARRY R. JACKSON AND HENRY A. MAY, OF CHICAGO, ILLINOIS.

GAS DISTRIBUTING AND GOVERNING VALVE.

Application filed December 2, 1920. Serial No. 427,906.

To all whom it may concern:

Be it known that we, HARRY R. JACKSON and HENRY A. MAY, both citizens of the United States, residing at Chicago, in the county of Cook and State of Illinois, have invented a certain new and useful Improvement in Gas Distributing and Governing Valves, of which the following is a specification.

Our invention relates to valves for promoting the efficiency of operation of internal combustion engines, more particularly by governing the flow of gas in the intake, not so much as to quantity passed as to the character of the gas stream and its position in the duct. One of the objects of the invention is to provide means for keeping the gas out of contact with the walls of the duct, especially when the duct is cold. Another object is to provide means for increasing the perturbation and venturi effect, thus increasing the nebulization and preventing the deposition of the fuel in the form of a fog or mist upon the sides of the duct. A contributing object is to render the device entirely automatic and able to govern itself as to position in accordance with the rate of flow of fuel to the engine. Another object is to provide means whereby at high speeds, a small quantity of air may be introduced into the gas stream from the sides of the duct, this extra supply of air being automatically cut off at lower engine speeds. We accomplish our objects by the mechanism illustrated in the accompanying drawings, in which—

Figure 1 is an assembly view showing the relative positions of the throttle valve and our distributing valve in the intake duct. In dotted lines this figure shows the position of the intake relatively to the manifold and to the engine itself.

Figure 2 is a longitudinal sectional view of the intake duct with our valve and the throttle valve shown in position. The plane of section is indicated by the dotted line 2—2, Figure 3.

Figure 3 is a plan section on the line 3—3, Figure 2.

Figure 4 is a sectional elevation on the line 4—4, Figure 2.

Figure 5 is a front view of the valve mounting and spring which controls it, and

Figure 6 is a detail of the equalizing mechanism for causing the two gates of the

valve always to swing equal amounts and in opposite directions.

Like numerals denote like parts throughout the several views.

In the form selected to illustrate the invention the internal combustion engine 1 and intake manifold 2 are indicated in dotted lines. Leading to the manifold is the intake duct which consists of two sections 3 and 4 which are flanged so that they can be bolted to an insert or connecting section 6. This connecting section has a central passage 8 which, when the parts are assembled, forms a part of the duct itself. The throttle valve 9 is so placed that the connecting section is between it and the manifold. Thus the amount of gas flowing in the duct is controlled by the throttle valve. Located within the connecting section are two gates 10 which are supported upon hinges 12 in such manner that when they are closed they extend obliquely inward and forward. According to the present design the hinges are cylindrical and imbedded in the side walls 14 of the connecting section. They protrude thru the walls at one point where they are fastened to a spring 15 which urges them to rotate in such direction as to close the gates. While the shape of the spring may be varied, it is illustrated in the form of a leaf spring coiled around the hinges and backed up by an adjusting screw 16. By turning the screw toward or away from the spring the tension thereof can be increased or decreased.

Near the marginal edges of the gates the inner surface is roughened at the point 18 for breaking up and agitating the gas as it passes. This produces a beneficial turbulence. It is desirable that the proximate edges of the gates shall not fit exactly together when closed, but that an opening 19 shall be left for permitting a slight stream of gas to pass at all times. In order to avoid eddy currents back of the gates which would tend to permit the heavier gas to collect there we make perforations 17 in the gates. These let small jets of gas pass thru which clear out the pockets and produce desirable agitation.

In our selected design the hinges serve not only to support the gates, but form valves for admitting air into the intake duct at high engine speeds. For this purpose a duct 20 is formed in each of the hinges in such position that when the gate is fairly

wide open the duct will register with an inlet port 21 in the side wall. This latter port is open to the atmosphere through a second port 22 as best shown in Figure 2.

5 In order to insure that the two gates will always move equal amounts, equalizing mechanism is provided. This consists of two arms 24 and 25 rigidly connected to the protruding end of the hinges. The arm 24 10 has a slot which receives a pin 26 fastened to the end of arm 25. These parts are best shown in Figures 3 and 6.

In operation, the flow of gas thru the intake duct is controlled by the throttle 9. 15 The tendency of the ordinary throttle, however, is to throw the gas toward the walls of the duct, especially at low engine speeds. This induces bad conditions because at low engine speed the walls of the duct are apt 20 to be cold, which causes a deposition of some of the gas in the form of a fog or beads of liquid. The gates 10, however, prevent such deposition by deflecting the gas stream toward the center of the duct, especially at 25 slow speeds; for the slower the gas flow, the closer the gates will swing toward each other. As the throttle is opened and a higher velocity of gas ensues, the gates open automatically under pressure of the gas 30 stream and will stand substantially in open position when the throttle is wide open. Thus there is an automatic compensatory effect for if the throttle is wide open, the engine will run at full speed and heat the 35 walls of the duct, thus preventing them from chilling the gas. Hence, no deposition will take place. But if the stream is throttled down, thus permitting the walls to become cooler, the stream will be deflected 40 away from the walls toward the center of the duct. In addition there is a pronounced venturi effect and furthermore, on account of the corrugations 18, the gas will be agitated, thus increasing the perturbation and 45 promoting thorough mixture of gas and air and avoiding any tendency of the gas to become deposited on the walls of the duct.

Our mechanism has another advantage in 50 that it causes air to be admitted from the atmosphere when the engine is running at high speed. That this is desirable is a fact recognized by most engineers, and in our device it is accomplished automatically for 55 when the throttle is wide open the pressure of the gas speed against the gates will cause them to open which will, in turn, bring the ducts 20 in the hinges into register with the ports 21 in the side walls of the connecting section. When the rate of gas flow decreases 60 the gates in moving toward each other will rotate the ducts 20 out of register with the ports 21.

From the foregoing it will be seen that 65 our device is not a primary controlling mechanism, for the speed of the engine is

controlled by the throttle 9 as in ordinary constructions. The function of the gates is to deflect the gas from the sides of the intake duct, especially at slow speeds when these sides would naturally be cool and hence 70 tend to gather small globules of gasoline in liquid form. At high speeds, however, these gates swing back so as not to interfere with the gas flow. At the same time they automatically admit air from the outside 75 directly into the intake at high speed but at slow speed shut off the connection.

It is well known with the ordinary carburetor and throttle valve that when the throttle valve is suddenly opened up wide 80 when the engine has been idling, there is a momentary drop in vacuum on the carburetor jets. This is due to well known causes and such conditions are known as "flat 85 spots" in the vacuum. One of the advantages of our invention is that it automatically does away with these "flat spots" and produces a constant velocity control on the fuel jets throughout the motor range. Our valve gates function somewhat after the manner of a venturi constriction, and as 90 they operate in harmony with the rate of flow through the duct, they do not suddenly open but open gradually, thus preventing sudden reduction of vacuum at the jet. If 95 our controlling device were absent, a sudden opening of the throttle would so increase the available area of the duct as to reduce the pull on the jets and thus momentarily reduce instead of increasing the fuel supply. Our 100 valve gates prevent this action by providing a constriction which opens gradually in proportion to the building up of speed of the engine.

Having thus described our invention, what we claim as new and desire to secure by Letters Patent is:

The combination with the intake duct of an internal combustion engine of a throttle valve in the duct located between the carburetor and the engine, a pair of gates located between the throttle and the engine, said gates extending from the sides of the duct obliquely inward and forward in the direction of flow, a pair of rockshafts partially embedded in the walls of the duct and carrying said gates to form hinges therefor, and means for yieldingly urging the gates toward each other, the duct having airholes for admitting air into the duct and the rockshafts having airholes passing through them and adapted to register with the airholes in the duct when the gate is swung away from closed position and to come out of register when the gate is approximately in closed position.

In witness whereof, we have hereunto subscribed our names.

HARRY R. JACKSON.
HENRY A. MAY.
